UNITED STATES PATENT OFFICE.

CLAUDE ASTOLFO CONOVER, OF NEWBURGH, NEW YORK.

PENCIL-SHARPENER.

1,270,119.

Specification of Letters Patent. Patented June 18, 1918.

Application filed November 13, 1917. Serial No. 201,877.

To all whom it may concern: Be it known that I, CLAUDE A. CONOVER, a citizen of the United States, and a resident of Newburgh, in the county of Orange and State of New York, have invented a new and Improved Pencil-Sharpener, of which the following is a full, clear, and exact description.

This invention relates to pencil sharpeners, and has for an object the provision of an improved construction which may be readily applied or removed from any ordinary pencil now on the market.

Another object in view is to provide a sharpener having a securing means at one end and a cutting means at the opposite end whereby the same may be mounted on the end of a pencil when not in use, and when in use may be removed and used substantially in the ordinary manner of sharpeners.

A still further object of the invention is to provide a sharpener formed with a body or casing in two parts and one or more cutting blades held in place thereby in such a manner as to cut substantially in a spiral when in use.

In the accompanying drawing:

Figure 1 is a side view of an embodiment of the invention, same being shown on a pencil with the pencil in use.

Fig. 2 is a side view showing the sharpener acting on a pencil for sharpening same.

Fig. 3 is a longitudinal vertical section, on an enlarged scale, of the sharpener shown in Fig. 1.

Fig. 4 is a transverse sectional view through Fig. 3 on line 4—4.

Fig. 5 is a perspective view showing the frame and knife in a slightly spaced relationship, while illustrating the particular construction and the way the parts are assembled.

Fig. 6 is a sectional view similar to Fig. 3, but showing a slightly modified form of the invention.

Fig. 7 is a transverse sectional view through Fig. 6 on line 7—7.

Fig. 8 is a view similar to Fig. 5, but showing the modified structure disclosed in Fig. 6.

Referring to the accompanying drawing by numerals, 1 indicates an ordinary pencil held by the hand 2 so as to write on the paper 3 in the usual manner. On the upper end of pencil 1 is a sharpener 4 provided with a or clamping member 5, said

clamping member having a tubular section 6 reinforced by beads or otherwise, which merges into a split section 7 and a threaded section 8. The split section 7 is intended to grip the pencil 1 while the threaded section 8 is intended to accommodate the threaded end 9 of the sharpener. The sharpener is formed with a casing comprising sections 10 and 11 as shown in Fig. 5, said sections being 65 tubular in cross section and tapering from the outer end to the base 12, said base 12 being solid and threaded for fitting section 8. A knife 13 is provided which fits into the section 10 and extends slightly beyond the 70 cutaway portion thereof, so that as the device is rotated the pencil may be sharpened as shown in Fig. 2 and the shavings pass out through the cutaway portion 14. The knife 13 is provided with a base 15 with threads 75 thereon registering with the threads on the base 12 so that when the parts are in contact they may be screwed into section 8 as shown in Fig. 3, and not only held in position, but held tightly together. Preferably 80 the knife 12 is provided with a flange 16 extending for the full length thereof which is clamped between one edge of section 10 and one edge of section 11 as shown in Fig. 4, whereby the knife is held against accidental 85 twisting.

In Figs. 6 to 8 inclusive, will be seen a slightly modified form of the invention, in which two blades 17 and 18 are provided, both of said blades acting similar to blade 13 90 in the preferred structure, but producing two cuts as more clearly illustrated in Fig. 7. The section 11 is cut away at 19 in this form of the invention so as to allow the discharge of the shavings. The edges of the 95 blades 17 and 18 as well as the edge of blade 13 is preferably somewhat curved or spiral, though substantially any shaped edge may be used without departing from the spirit of the invention. The curving of the edges of 100 the blades is intended to give the same a shearing action rather than a scraping action whereby there will be a cleaner cutting of the wood on the pencil and a better sharpening of the lead. By forming the 105 parts comparatively small and connecting same with the clamping section 7 the sharpener is always convenient and may be used at any time, while not being in the way, either in the pocket or while the device is in use.

What I claim is:

1. A pencil sharpener of the character

described comprising a clamping member formed with a clamping section for fitting the end of a pencil, a threaded section, and a sharpening member comprising a cutter, 5 and a casing, said cutter and casing being formed with threads for interlocking with the threads of said threaded section.

2. A pencil sharpener comprising a casing having a pair of hollow tapering sections merging into a threaded base, one of said sections being formed in one of said sections, said cutter having a base extending to a point between the base of said first mentioned section and a tubular threaded member fitting into said base for locking said sections together and said cutter in place.

3. A pencil sharpener comprising a casing having a cutaway portion for receiving a knife arranged in said casing, said knife being formed so that the edge will substantially conform to the edge of a pencil, said casing being formed in two sections, and said knife having a base extending between the base of said sections and a clamping member for clamping said sections together, and a knife in position in the casing.

4. In a pencil sharpener of the character described, a threaded supporting member, a casing formed with two parts having a threaded base screwed into said threaded supporting member, and a knife fitted into said casing having a threaded base, said knife being fitted between the bases of said casing.

5. A pencil sharpener comprising a sup-

porting member having a clamping section for fitting a pencil, a threaded section, a casing having a base, a knife having a base, said knife fitting in said casing, the base of said knife with the base of said casing being threaded for fitting into said threaded section, and means on the knife for preventing an independent rotation thereof.

6. In a pencil sharpener of the character described, a supporting member comprising a clamping section for clamping the end of a pencil, a threaded section, a casing divided into parts, each of said parts having a threaded base, and a knife arranged in said casing having a threaded base, said knife having a flange extending from one edge projecting between said sections whereby when the sections and knife are screwed into said threaded section the casing and knife will be clamped together and the knife held 55 against independent rotation.

7. A pencil sharpener comprising a supporting member having a clamping section for fitting a pencil, a threaded section, a casing divided into parts, each of said parts having a threaded base, and a pair of knives or cutters arranged in said casing, the cutting edges of said knives being substantially diametrically opposite, said knives having a threaded base positioned between the base of said sections, when said bases are screwed into said threaded sections the casing and knives will be rigidly held together as a unit.

CLAUDE ASTOLFO CONOVER.
